UNITED STATES PATENT OFFICE.

THOMAS H. PARKER, OF SAN FRANCISCO, CALIFORNIA, ASSIGNOR TO UNDERWRITERS UTILITIES CORP., OF SAN FRANCISCO, CALIFORNIA, A CORPORATION OF CALIFORNIA.

FIRE EXTINGUISHER.

Application filed October 8, 1923. Serial No. 667,249.

This invention relates to a fire extinguisher, and more particularly to a chemical type of extinguisher that is light and portable for manual use.

5 In the usual type of chemical extinguisher, a liquid of desirable extinguishing properties is confined in a space, and provisions are made for ejecting this liquid whenever the extinguisher is to be used. This liquid may 10 be carbon tetrachloride or the like. In one type of extinguisher, gas pressure is provided to perform the function of ejecting the liquid in a stream, which is so essential to convey it to the desired burning locality. It is one of 15 the objects of my invention to provide such a fire extinguisher in which there is a certainty that the gas under pressure (usually compressed air) is prevented from leaking out of the container while the extinguisher is 20 inactive, and thus from making it useless when its need arises. This feature is of very great importance, because an extinguisher may be kept on hand for an emergency for 25 a considerable period of time—sometimes years—before the emergency actually arises. Thus if the gas is permitted to leak out, even at a very slow rate, the extinguisher becomes entirely valueless.

It is another object of my invention to 30 provide a fire extinguisher of an improved, simple construction, and having but a few parts, but all of which are capable of remaining in proper operative condition for a long period.

35 It is still another object of my invention to render it extremely simple to determine whether the gas pressure is still large enough to operate the extinguisher.

It is still another object of my invention to 40 provide a fire extinguisher having a container that increases in volume as pressure is applied in the process of charging.

In many respects, my invention is not limited to fire extinguishers, as many features 45 thereof can be used in connection with other articles.

50 My invention possesses other advantageous features, some of which with the foregoing, will be set forth at length in the following description, where I shall outline in full that form of the invention which I have selected for illustration in the drawings accompanying and forming part of the present invention. Although in the drawings I have 55 shown but one embodiment of my invention,

I do not desire to be limited thereto, since the invention as expressed in the claims may be embodied in other forms also.

Referring to the drawings:

Figure 1 is a cross sectional view of a 60 complete extinguisher embodying my invention;

Fig. 2 is a side elevation of the extinguisher, indicating its appearance when in proper operative condition;

Fig. 3 is a side elevation similar to Fig. 2, 65 but illustrating the container when in an inoperative condition;

Fig. 4 is an enlarged sectional view of the 70 nozzle mechanism of the extinguisher, with some of the parts separated as before assembly, for the purpose of more clearly indicating the manner of construction; and

Fig. 5 is a view, partly in section, of a 75 portion of the device, together with apparatus that may be used for charging and sealing it.

One of the features of my invention resides in the construction of the container 11 in which the chemical 13 is disposed, and 80 which is filled to about the level 12. Above this liquid the gas under pressure is located, and thus the entire interior of the vessel 11 is subjected to a comparatively large expanding force. The container 11 is made of thin 85 resilient metallic material in the form of a drum, so that when there is sufficient gas pressure, the sides thereof are forced outwardly, as indicated in Fig. 2. In this way a round appearance is imparted to the container, and this appearance serves as an 90 indication of the internal pressure. The free condition of the container 11, with pressure released, is shown in Fig. 3. The sides 14 form an exterior concave surface.

These sides 14, forming a portion of the boundary for container 11, thus respond so far as their physical form is concerned, to pressure conditions within the container. But in addition to this function, it is to be 100 noted that there is a substantial increase in volume when the container 11 is operative, so that a large quantity of liquid 13 may be accommodated. In effect the sides 14 thus form diaphragms against which the gas 105 pressure may act.

In order to permit the escape of the liquid 13, I provide a swinging pipe or connection 15, the open end of which is shown as weighted as at 16, so as to maintain the 110

connection 15 substantially vertical and its open end near to the bottom of the container 11. In this way there is an assurance that substantially all of the liquid 13 may be used when the extinguisher is placed in operation. This connection is shown as supported in a swinging manner with a stationary pipe or conduit 17. A bracket 18 may if desired be provided to brace the conduit 17. This bracket is shown as conveniently supported on the boss 19 of a handle 20, which boss projects into the container as shown in Fig. 1. The handle 20 is provided with the pair of feet 21 and 22 by the aid of which it is spaced from the container top, and is supported thereon in any appropriate manner.

The handle 20 also serves conveniently to conduct the liquid 13 out of the container 11, and for this purpose it is provided with passageways 23 and 24, respectively through the foot 21 and the body of the handle. The passageway 23 communicates with the conduit 17, while the passageway 24 extends from said passageway 23 to a nozzle supporting extension 25 that is substantially coaxial with said latter passageway. Screws or other plugs 26 and 27 are fitted into the ends of the passageways where they are drilled, so as to maintain the entire space air tight. The ends of these screws may in addition be sealed with solder, such as shown at 28 for example; this solder seal may be dropped readily into the tapered countersink 35 provided therefor.

The extension 25 has a bore 29, the end of which is hermetically sealed by a thin disc-like closure 30. The extension 25 and its associated parts are most clearly illustrated in Fig. 4. The closure 30 may be fastened in an airtight manner to the end of extension 25, as by soldering. Furthermore this closure is made of such thin sheet metal that under ordinary conditions it can readily be ruptured by the pressure existing in the container 11. This can readily be accomplished by making the closure from some comparatively weak and pliable metal such as tin or zinc. However, it is essential not to permit this rupture to take place until the extinguisher is to be used. To effect this result, a cap 31 is provided, which has a flat shoulder 32 adapted to be placed close up against the closure 30 and thereby serve to support it against expansion or bulging outwardly under the influence of the gas pressure in container 11. This cap 31 is arranged to be readily placed over the extension 25 or to be withdrawn therefrom. For this purpose the end of extension 25 is provided with external threads 33, which however occupy only a portion of the complete circumference of extension 25. The remainder of the circumference is grooved or rifled. Substantially the same kind of threads 34 is

provided for the interior of cap 31, whereby it is possible to engage or disengage the threads 33 and 34 by turning the cap 31 through a comparatively small angle. Therefore to place the cap 31 over the extension 25, it is merely necessary to slip it over the threads 33, while these threads occupy different portions of the circumference than the threads 34. Then while the cap 31 is pressed firmly in place, it may be given a small turn, whereby the threads will engage and the cap will be held in place. The cap in this position will effectually prevent the rupturing of closure 30. Whenever the extinguisher is to be used, the cap 31 may readily be removed by the reverse process, and the disc 30 will then be ruptured and will permit the escape of the liquid 13. As the liquid escapes, the walls 14 gradually assume the collapsed position of Fig. 3; this action serves to maintain the gas pressure at its proper high value throughout the period of discharge.

While of course as thus far described, the apparatus is quite practical, I find it advantageous to provide a more conventional type of nozzle for the outlet, whereby it is ensured that the liquid 13 will issue from the extension 25 in a continuous and well-defined stream. A slideable nozzle 35 is for this purpose supported within the bore 29 of extension 25. When the gas pressure is free to act, it forces the nozzle 35 axially along the bore 29 and through the closure 30. It is stopped from coming entirely out by a ring key 36 placed along the inner circumference of the bore 29. The liquid 13 will then flow out of the nozzle 35.

The manner in which the container 11 may be charged with compressed air or other gas under pressure is illustrated in Fig. 5. Of course other ways of accomplishing the same result may be used, but the scheme shown has the advantage of comparative simplicity. First the container 11 is filled with the liquid 13, and then it is made airtight except for the threaded aperture 37 that extends from the passageway 24 in the handle. This airtight condition is secured by properly fastening in the screw 27, and by fastening the sealing closure 30 on the end of extension 25. The cap 31 is also held on this extension, to prevent the closure from being blown out. A casing 38 is then slipped over the tapered end 39 of handle 20, in such a way that a tight fit is ensured. This casing connects as by a flexible hose 40 with a source of compressed air. There are provisions for screwing in the plug 26 while the air is maintained under pressure in the casing 38. For this purpose, the plug is held in the end of a manually rotatable rod 41 which extends outside of casing 38, and which is axially aligned with the aperture 37. This rod 41 passes through a packing gland in

cluding the packing 42 and stuffing nut 43, whereby the chamber in casing 38 may be maintained airtight. The plug 26 is threadedly engaged in the end of rod 41, which 5 after the air pressure is applied, may be slid toward the aperture 37, the countersink 44 acting as a guide for the plug 26. The rod 41 may now be rotated to fasten this plug 10 tightly in place, and then it may be freed therefrom by rotating it in the opposite direction. As soon as this is accomplished, the air pressure in casing 38 may be reduced 15 by proper operation of valves, and this casing may be removed from extension 39. A solder seal may now be placed in the countersink 29, before any material leakage can 20 take place. Preferably the plug 26 is made from some composition metal so that the exposed end may be sealed by simply touching it with a soldering iron.

The extinguisher is now in proper condition for storage or for immediate use. Due to the fact that the container 11 is hermetically sealed, there is no danger of its losing 25 its charge of compressed air even after a considerable period of time. Furthermore, the seal may be broken without any waste of time should the emergency arise that necessitates the use of the extinguisher.

30 In the claims, the seal is defined as combined molecularly with the vessel or container. This term is intended to cover such equivalent forms of union as soldering, brazing or welding.

35 I claim:

1. A chemical fire extinguisher comprising an airtight metallic container having at least 40 a part of its boundary defined by a wall the form of which is dependent upon the conditions of pressure within the container, and a fluid under pressure in the container.

2. A chemical fire extinguisher comprising an airtight metallic container having a wall 45 in the form of a thin diaphragm that is expanded in response to pressure conditions in the container, said diaphragm being concave under atmospheric pressure and convex under the operating pressure of the extinguisher, and a fluid under pressure in the container.

50 3. A chemical fire extinguisher comprising a metallic container, a closure for said container, said closure being of such a nature that the pressure in the container is sufficient to destroy its sealing property, means 55 for preventing the pressure from producing this effect, and a nozzle member adapted to be moved by the pressure in the container so as to direct the stream after the closure is permitted to be destroyed.

60 4. A chemical fire extinguisher comprising a metallic container, a fluid under pressure in said container, a closure for said container, said closure being formed of a wall

of material incapable by itself of withstanding the pressure in the container, means for supporting the wall against rupture, and a nozzle member adapted to be moved by the pressure in the container so as to direct the stream after the wall is permitted to be ruptured.

65 5. In combination, a container, a fluid substance under pressure in said container, an extension on said container having an aperture in communication with the interior of said container, a closure for said aperture, said closure being formed of a material incapable by itself of withstanding said pressure, and a manually removable cap on said extension directly reenforcing said closure.

70 6. A chemical fire extinguisher comprising a metallic container, a fluid under pressure in said container, said container having an extension, a closure for said extension, formed of a wall of material incapable by 75 itself of withstanding the pressure in the container, a cap fitting over the extension and readily detachable therefrom, for supporting the wall against rupture, and a nozzle member slidably in said extension and 80 adapted to be moved by the pressure in the container so as to direct the stream after the wall is ruptured.

85 7. In a chemical fire extinguisher, a metallic container having a side wall formed 90 of a thin resilient member providing a resilient diaphragm that is permitted to collapse only when there is no substantial pressure in the container, a chemical liquid under pressure in said container, a member forming 95 an extension for conducting the liquid out of the container, a wall hermetically closing the extension but incapable by itself of withstanding the pressure within the container, and a cap fitting over the extension 100 and supporting the wall against rupture.

105 8. A chemical fire extinguisher comprising a metallic container having collapsible walls, liquid in the container, a gas under 110 pressure in the container serving to dilate the walls thereof and thereby to increase the volume of the container and means for discharging said liquid.

115 9. In combination, a container, a fluid substance under pressure in said container, an extension on said container having an aperture in communication with the interior of said container, a closure mounted at the extremity of said extension for sealing said 120 aperture, said closure being formed of a material incapable by itself of withstanding said pressure, and a manually removable cap secured to the extremity of said extension and reenforcing said closure.

125 In testimony whereof, I have hereunto set my hand.

THOMAS H. PARKER.
